UNITED STATES PATENT OFFICE

145,783

DESIGN FOR A BRACELET OR SIMILAR ARTICLE

Jacques Bernas, New York, N. Y.

Application January 26, 1946, Serial No. 125,994

Term of patent 14 years

(Cl. D45—4)

To all whom it may concern:

Be it known that I, Jacques Bernas, a citizen of the United States, resident of New York, in the county of New York, State of New York, have invented a new, original, and ornamental Design for a Bracelet or Similar Article, of which the following is a specification, reference being had to the accompanying drawing, forming part thereof.

In the drawing,

Figure 1 is a top plan view of a bracelet showing my new design, the links being repeated throughout the length of the article as indicated by the broken line illustration, and

I claim:

The ornamental design for a bracelet or similar article, substantially as shown and described.

JACQUES BERNAS.
